UNITED STATES PATENT OFFICE.

HARRY S. OLGARD, OF SUTTON, NORTH DAKOTA.

OIL CAN.

Application filed June 30, 1922. Serial No. 571,969.

To all whom it may concern:

Be it known that I, HARRY S. OLGARD, a citizen of the United States, residing at Sutton, in the county of Griggs and State of North Dakota, have invented a new and useful Improvement in Oil Cans, of which the following is a specification.

My invention relates to oil cans and has for its object to provide an oil can formed 10 with a nozzle, through which the oil may be forced, with the nozzle in an upright position.

Another object of the invention is to provide a horizontally positioned pump, placed 15 within the oil can, which pump is connected with a valve chamber, leading up to the nozzle of the can.

A still further object is to provide a handle for carrying the can and a second 20 movable handle, positioned outwardly from said first handle and connected to said pump, which latter handle is adapted to operate the pump, as both of these handles are simultaneously grasped and pressed together.

25 A still further object is to provide a removable valve cage, permitting the removal of the valves, for the purpose of cleaning and examining the interior of the device.

The full objects and advantages of my invention will appear in connection with the 30 detailed description thereof, and are partly pointed out in the claims.

In the drawings forming part of this specification:

35 The figure is a sectional view of my invention.

My invention is clearly shown in the drawing, comprising an oil can A, which is formed with a cylindrical portion 10, to 40 which is soldered a dome shaped head 11 and a bottom 12. On the exterior of the cylindrical portion 10, is attached a handle 13, which is securely riveted thereto, and which is positioned near the central portion of the oil can. Upon the central portion of the dome shaped head 11, I attach a nozzle 14, the extreme end 15, of which may be bent outwardly as shown. This nozzle is attached to the head 11, in a manner to be 45 later described. In an opening in this head, I provide a filler plug 16 which is screwed into a member 17, soldered to the said head 11, by means of which the oil in the can can be replenished at will.

50 The pump portion of my invention consists of a horizontally positioned cylinder

18, which extends partly across the interior of my oil can A, immediately below the handle 13. This cylinder projects through the shell for a short distance and is securely 60 soldered thereto. Upon the exterior of said cylinder, I provide a cap 19, for partly closing the same. Within the interior of the cylinder 18, is mounted for reciprocation, a piston 20, which has a lug 21 secured to the 65 outer end thereof. This piston may be constructed in any suitable manner, employing leather plungers 22 or other suitable devices.

The device for operating piston 20, consists of a bent handle 23 which is positioned 70 outwardly from the handle 13 and is pivoted at its upper end 24 to a lug 26, riveted to the can A, near the top thereof. The lower end 27 of handle 23 is pivoted to a link 28 which in turn is pivoted to the lug 21, secured to piston 20. The operation of the device is as follows: When the fingers of the user are inserted through handle 13, and the palm of the hand pressed against handle 23, said handle 23 is caused to move toward 75 handle 13, thereby forcing the piston 20 inwardly in the cylinder 18. For bringing piston 20 back to its initial or outward position, I provide a coil spring 29 which is positioned in the interior of cylinder 18 and 80 acts against the end of piston 20, to force the same outwardly as shown.

The valve mechanism of my invention consists of a cylindrical valve casing 30 which is positioned at right angles to the 85 cylinder 18 and is securely soldered thereto. An opening 31 in the side of casing 30 in proximity to cylinder 18, provides communication from the said cylinder 18 to the valve chamber of the invention. A cap 90 32 attached to the top of casing 30 has soldered to it a pipe 33 which leads upwardly and connects with the nozzle 14 at 34. This structure permits of readily removing the nozzle 14 for the purpose of cleaning 100 the same and the pipe 33.

The valves proper are constructed as follows: Within the casing 30 is positioned a cylindrical cage 38 which is formed with a partition 39 across the center of the same, 105 and a partition 40 at the bottom thereof, both of which are securely soldered in place. The extreme end of the cage is theaded as indicated at 41 so that the said cage may be readily screwed into the casing 30 at will. A 110 conical opening 42 is provided in the partition 39 which forms a valve seat and a pas-

sageway leading to the chamber 43 at the upper portion of the cage 38 from the chamber 44 at the lower portion thereof, which latter chamber in turn communicates through an opening 45 in cage 38, registering with the opening 31 and the said opening 31 with the interior of the cylinder 18. In a similar manner, a conical opening 46 in the partition 40, provides a valve seat 10 and a passageway leading from the chamber 44 to the interior of the oil can A. Secured to the upper portion of the partitions 39 and 40 are two U-shaped brackets 47 and 48 having cross bars 49 connected therewith. In these cross bars are slidably mounted valve stems 50 and 51 to which are attached valve heads 52 and 53, adapted to seat against the seats 42 and 46, previously referred to. Two compression coil springs 20 54 and 55, which act against the valve heads 52 and 53 and the bars 49, serve to hold said valves normally in closed position. For removal of the cylindrical cage 38 and the valves connected therewith, I provide 25 a plug 56 which is screwed into the bottom of the oil can A.

The operation of the device is as follows: When piston 20 is forced in the cylinder 18 against the pressure of spring 29, the fluid within said cylinder and chamber 44 is compressed causing the valve 52 to be raised and permitting the fluid to escape into the chamber 43 and through the pipe 33 and nozzle 14. As the piston 20 is caused to travel in the opposite direction by spring 29, valve 52 is closed while a suction is created in chamber 44 which opens valve 53 and causes the oil in the can to flow from the bottom past the valve 53 into chamber 44 and cylinder 18. Upon continual operation of piston 20, it can readily be seen that oil can be forced through nozzle 15 and directed wherever required.

My invention is particularly useful for oiling where the oil cannot be delivered by the usual oil can, inasmuch as the invention may be used in either a vertical or horizontal position. In addition, the oil may be discharged from the same, with sufficient force and in sufficient volume to reduce the time required when a considerable amount of oiling is to be done. All of the parts including the piston, valve, casing and nozzle of the invention may readily be removed so that all of the parts may be examined, cleaned and repaired, thereby providing a highly useful and serviceable oil can.

In accordance with the patent statutes I have described the principles of operation of my invention together with the apparatus which I now consider to represent the best embodiment thereof, but I desire to have it understood that the construction shown is only illustrative and that the in-

vention can be carried out by other means and applied to uses other than those above set forth within the scope of the following claims:

I claim:

1. An oil can comprising a casing, a dome-shaped cover for said casing, a cylinder horizontally positioned at the lowermost portion of said casing within the same, said casing communicating in one side with the exterior, said cylinder being rigidly attached to said casing and extending substantially across said casing, a vertically positioned valve chamber attached to said cylinder and communicating therewith, said valve chamber being positioned near the opposite side of said casing, said valve chamber being of cylindrical formation and having an opening at its lower portion directed toward the bottom of said casing, said casing having an opening in the bottom thereof registering with the opening in said valve chamber, a tubular valve cage having a bottom therein and an intermediate partition, valves formed in said cage bottom and partition, said cage and valve mechanism being adapted to be placed through said opening in said casing bottom and into said valve chamber and secured therein with said lower valve in close proximity to the bottom of the said casing and below said cylinder and with said upper valve above said cylinder, a cap for closing the opening in said casing bottom, a nozzle attached to said casing cover and an inclined pipe connecting said valve chamber with said nozzle.

2. An oil can comprising a casing, a dome-shaped cover for said casing, a cylinder horizontally positioned at the lowermost portion of said casing within the same, said casing communicating in one side with the exterior, said cylinder being rigidly attached to said casing and extending substantially across said casing, a vertically positioned valve chamber attached to said cylinder and communicating therewith, said valve chamber being positioned near the opposite side of said casing, said valve chamber being of cylindrical formation and having an opening at its lower portion directed toward the bottom of said casing, said casing having an opening in the bottom thereof registering with the opening in said valve chamber, a tubular valve cage having a bottom therein and an intermediate partition, valves formed in said cage bottom and partition, said cage and valve mechanism being adapted to be placed through said opening in said casing bottom and into said valve chamber and secured therein with said lower valve in close proximity to the bottom of said casing and below said cylinder and with said upper valve above said cylinder, a cap for closing the opening in said casing bottom, a nozzle attached to said casing cover,

an inclined pipe connecting said valve chamber with said nozzle, a piston movable within said cylinder, a spring for holding said piston in outward position, a looped handle secured to said casing immediately above said cylinder, a second handle similar in formation to said first handle pivoted at its upper portion to the top of said casing and enveloping said first handle and a horizontally positioned link pivoted to said piston at one end and to the lowermost portion of said second handle at its other end.

3. An oil can comprising a casing, a nozzle attached to the top thereof, a cylinder positioned inwardly within said casing, horizontally positioned relative thereto, a vertically extending valve casing positioned within said oil can casing and rigidly secured to said cylinder, a pipe leading from said valve casing to said nozzle, valves within said valve casing and a piston within said cylinder.

4. An oil can comprising a casing, a horizontally positioned cylinder, located within

said casing, near the bottom thereof, a vertically positioned valve casing, positioned 25 within said oil can casing attached to said cylinder, an opening in the bottom of said oil can and a cage having valves mounted thereon, insertable through said opening and adapted to be secured within said valve casing.

5. An oil can comprising a casing, a cylinder, a cylindrical valve casing secured to said cylinder and positioned at right angles to said cylinder, an opening through the bottom of said oil can casing, registering with the end of the said valve casing, a tube adapted to be inserted into said valve casing, partitions formed in said tube, valve seats formed on said partitions, brackets attached 40 to said partition, valves slideable within said brackets, adapted to seat against said valve seats and means for securing said tube and valves within said valve casing.

HARRY S. OLGARD.
